Inventor
John P. S. Voght.

UNITED STATES PATENT OFFICE.

JOHN P. S. VOGHT, OF DENVER, COLORADO.

SEAL-PRESS.

SPECIFICATION forming part of Letters Patent No. 361,972, dated April 26, 1887.

Application filed October 3, 1885. Serial No. 178,864. (No model.)

To all whom it may concern:

Be it known that I, JOHN P. S. VOGHT, a citizen of the United States, residing at the city of Denver, in the county of Arapahoe and State of Colorado, have invented a new and useful Improvement in Seal-Presses, of which the following is a specification.

My invention relates to improvements in seal-presses in which the dies are removable and adjustable; and the objects of my improvements are, first, to provide removable and adjustable dies for a seal-press independent of the press itself; second, to afford facilities for the proper adjustment of dies to any seal-press, and, third, to make the use of one press alone necessary in all cases. I attain these objects by the mechanism or parts illustrated in the accompanying drawings, in which—

Figure 1 is a side elevation of the press. Fig. 2 is a sectional plan view of the press. Fig. 3 represents a plan and vertical central sectional view of the interchangeable male die. Fig. 4 represents a plan and side view of a ring, preferably of steel. Fig. 5 is a plan and side elevation of the interchangeable female die. Fig. 6 is a transverse vertical section on line X X of Fig. 1, showing the dies in position.

Similar letters refer to similar parts throughout the several views.

A is a transverse key-slot in the end of the

plunger of the press for receiving the beveled and wedge shaped key G of the interchangeable female die.

B is a hole in the lower plate of the press for receiving the projection D on the bottom of the adjustable male die, and E is a hole in the bottom of the adjustable male die for receiving the pin C in the lower plate of the press, which combine to hold the male die in its place.

F is a ring, preferably of steel, which moves on the plunger of the press and is pressed down over the key G of the adjustable female die after the die is placed in its position on the plunger, which ring aids in holding the female die in proper position. The slot A is dovetailed and corresponds in shape with key G, and when the parts are in position the ring F encircles the plunger at the point of engagement of the key and slot.

What I claim as my invention, and desire to secure by Letters Patent, is—

The combination of the plunger having a dovetailed slot, A, with a die having a correspondingly shaped key, G, and a ring, F, encircling the plunger at the point where the key engages with the slot.

JOHN P. S. VOGHT.
